UNITED STATES PATENT OFFICE.

CATHARINE A. GRISWOLD, OF NEW YORK, N. Y.

DESIGN FOR THE ORNAMENTATION OF CORSETS.

SPECIFICATION forming part of Design No. 19,240, dated July 30, 1889.

Application filed June 29, 1889. Serial No. 316,100. Term of patent 14 years.

To all whom it may concern:

Be it known that I, CATHARINE A. GRISWOLD, of the city, county, and State of New York, a citizen of the United States, have 5 invented and produced a new and original Design for the Ornamentation of Corsets, of which the following is a full, clear, and exact description, reference being had to the accompanying drawing, forming part of this specification.

The single figure in the drawing represents in side elevation a corset containing my invention.

The leading and special feature of my new 15 design consists in bands or stripes, each one of which is curved or bent upon itself about midway its ends, and said ends of which are approximately rectilinear in direction and converge toward each other at their free extremities, said bands or stripes thus shaped extending in a series longitudinally across the 20 corset between the top and bottom edges thereof.

A represents a corset, which may be in the 25 usual and ordinary form.

B B' B² represent bands or stripes, each one of which has a curve or bend b upon itself about midway its ends, and said ends of which, as at b' b², are approximately rectilinear in direction and converge toward each other at their 30 free extremities, as shown. These bands or stripes B B' B² thus shaped extend in a series in succession longitudinally across—namely, up and down—the corset between the top and bottom edges thereof, as shown. 35

What I claim is—

The design for the ornamentation of a corset herein described and shown, the same consisting in bands or stripes B B' B², each one of which has a curve or bend b upon itself about 40 midway its ends, and said ends b' and b² of which are approximately rectilinear in direction and converge toward each other at their free ends, said bands or stripes extending in a series longitudinally across the corset between the top and bottom edges thereof. 45

CATHARINE A. GRISWOLD.
